UNITED STATES PATENT OFFICE

EDWARD F. WATSON, OF LARCHMONT, NEW YORK, ASSIGNOR TO AMERICAN TELEPHONE AND TELEGRAPH COMPANY, A CORPORATION OF NEW YORK

ELECTRICAL PICTURE TRANSMISSION

Application filed February 12, 1927. Serial No. 167,784.

This invention relates to electro-optical transmission and more particularly to a picture transmission system in which the picture characteristics are transmitted by current impulses of varying duration.

It is an object of the present invention to provide simple means to convert the light effects of elemental areas of an object into electrical code impulses.

In the attainment of this object, a relay is preferably employed to control the duration and character of the impulses impressed upon a transmission circuit. This relay is energized by cyclically varying current of constant amplitude which causes periodic impulses to be transmitted. This current preferably varies linearly, that is, it is of "saw-toothed" wave form. The bias of the relay is controlled in accordance with the tone values of the elemental areas of the picture or object at the transmitter, thus causing corresponding variations in the durations of the impulses transmitted.

The invention contemplates obtaining the cyclically varying current by alternately charging a condenser through a resistance by currents of opposite polarities and operating the relay as a leak on the condenser, the current through the relay being proportional to the voltage across the condenser.

The invention also contemplates obtaining the cyclically varying waves by alternately applying voltages of opposite polarities to a series circuit containing inductance and resistance and operating the relay by the current through the inductance.

The arrangements for obtaining alternating current of saw-toothed wave form are adapted to be used in other fields than that of electrical picture transmission. The appended claims are drafted in contemplation of such use.

A more detailed description of the invention follows and is illustrated in the accompanying drawing.

Fig. 1 is a schematic diagram of an electrical picture transmission system wherein the signal forming relay is operated as a leak on the condenser of the source of cyclic current;

Fig. 2 is a modified arrangement wherein

voltages of opposite polarities are impressed through a resistance upon an inductance to produce cyclically varying current, the inductance being that of the signal forming relay winding;

Fig. 3 is a further modification wherein the cyclic current is of sinusoidal wave form;

Figs. 4, 5 and 6 are diagrams illustrating the nature of the transmitted impulses and the manner of their production.

Referring now to Fig. 1 of the drawing, relay 5 controls the transmission of current impulses over line 6 from grounded batteries 7 and 8, the duration of the impulses being characteristic of the tone values of successive elemental areas of a transmitted picture. The operation of relay 5 which is a polar relay of well known type, is controlled by three kinds of energizing current. A steady bias of the relay is obtained by current from battery 9 through winding 10. The amplitude of this biasing current is controlled by resistance 36. A cyclically varying energization is obtained by current through winding 11. A variable bias is produced by picture current of varying amplitude flowing through winding 12. The combined action of these three currents causes the armature of relay 5 to vibrate from its spacing (S) to marking (M) contacts and vice versa at a rate determined by the frequency of the cyclically varying current while the periods of closure of the spacing and marking contacts are determined by the steady bias in cooperation with the varying bias.

The source of cyclically varying current in Fig. 1 consists of a condenser 13 and a resistance 14 connected in series with grounded batteries 15 and 16 of opposite polarities through the vibrating armature 17 of relay 18. The voltage across the condenser 13 is impressed upon the winding 11 of relay 5 through the resistance 19. By properly choosing the rate of vibration of the armature 17, the voltage of batteries 15 and 16 and the constants of condenser 13 and resistances 19 and 14, the current impressed upon winding 11 of relay 5 may be given a saw-toothed wave form like that shown by graph P in Fig. 5.

Vibrating relay 18 is a simplified form of the Gulstad vibrating relay. The simplification consists in the omission of the line winding so that the operation of the relay is controlled entirely by the constants of the condenser 20, resistances 21 and 22 and the inductances of the accelerating winding 23 and the opposing winding 24. For a more detailed description of the operation of this relay reference may be made to pages 287 to 290 of a book by H. H. Harrison "Printing Telegraph Systems and Mechanisms" published by Longmans, Green and Company, New York, 1923.

If the relay 5 were energized solely by cyclically varying current of wave form P shown in Fig. 5, its armature would vibrate from spacing to marking and vice versa at the same rate that the armature 17 of relay 18 vibrates. The durations of the spacing and marking intervals would therefore be substantially equal. The effect of the steady biasing current from battery 9 through winding 10 is to tend to cause the armature to move to the marking (M) contact and therefore to change the relative durations of the spacing and marking intervals. The action of the negative half waves of the cyclically varying current to return the armature to the spacing position may be completely neutralized or so nearly so that the spacing interval is of very short duration.

The picture current flowing through winding 12 then opposes the steady bias so that the actual bias may vary from minus 100% to plus 100%.

In this specification and the accompanying drawings the convention followed with regard to the effect of current in the windings of relays 5 and 40 is that when the voltage applied to the upper terminals is positive, the tendency is to move the armature to the marking contact, and when the voltage is negative the tendency is to move the armature to the spacing contact.

The picture current is produced in well-known manner and is a uni-directional current varying in amplitude corresponding to the tone values of successive elemental areas of an object or picture to be transmitted. As shown in Fig. 1 a transparency 25 of the picture to be transmitted is mounted on a drum 26 which is adapted to be given a motion of rotation around its axis and of translation in the direction of the axis. The rotation of shaft 27 by a suitable source of power causes the rotation of the drum 26 through gears 28 and 29 and the longitudinal movement of the drum 26 by the movement of carriage 30 along the support 31 by means of screw threads on the shaft 27 engaging a nut on the carriage 30. Light from a source 32 is focused by means of lens 33 on the surface of the transparency 25. The light passing through the transparency

enters photoelectric cell 34 and the amount of this light is determined by the tone value of the elemental area through which the light is passing. The current flowing through the photoelectric cell is amplified preferably in an electron discharge amplifier 35 the output current of which flows through the winding 12 of relay 5. For a more detailed description of this arrangement for producing picture currents reference may be had to Patent No. 1,654,374, Dec. 27, 1927, of J. W. Horton.

The effect of varying the bias of relay 5 is shown in Figs. 4 and 5. To explain this effect let it first be assumed that relay 5 is being energized solely by current of saw-toothed wave form P flowing in winding 11. The positive half waves above the zero line 0 will then (by convention) cause closure of the marking contact and the negative half waves below line 0 will cause closure of the spacing contact. Since the positive and negative half waves are substantially equal the marking and spacing contacts will be closed for substantially equal intervals.

Next assume that the steady biasing current I_s becomes effective through winding 10. The positive voltage from battery 9 being connected to the upper terminal of winding 10, the effect of the biasing current is to tend to cause closure of the marking contact. This may be represented in Fig. 5 by moving the reference line 0 to the position $0'$. With respect to the new reference line $0'$ the graph P represents the combined energization of relay 5 due to the current of saw-toothed wave form P and the steady biasing current I_s . When this graph extends above line $0'$, which for the assumed value of I_s is all the time, the marking contact of relay 5 is closed. This represents the condition of plus 100% bias.

If now the picture current becomes effective in winding 12 and since the upper terminal of winding 12 has a negative voltage impressed thereon, the effect of this current is to oppose the effect of the steady biasing current. The effect of this current is represented in Fig. 5 for one condition by I_A and the effect on relay 5 may be represented in Fig. 5 by moving the reference line from the position $0'$ to the position 0_A . The armature of relay 5 will therefore be moved to close the marking contact for a period t_m during each cycle while the graph P is above the reference line 0_A and to the spacing contact for a period t_s , while the graph is below the reference line 0_A .

Similarly for other values of picture currents represented by I_B , I_C , I_D and I_E the reference lines in Fig. 5 become 0_B , 0_C , 0_D and 0_E . When the picture current has a value I_E the armature of relay 5 will be moved to a position to close the marking contact for a period t'_m and the spacing contact for a period t'_s .

period t' , during each cycle. The corresponding marking and spacing intervals for the several conditions are represented by the graphs A, B, C, D and E in the lower part of Fig. 5. It may be noted that for a value of picture current represented by I_c the new reference line O_c coincides with the base reference line 0 for zero bias and the marking and spacing intervals are of substantially equal duration.

The current impulses transmitted to the line 6 for the several conditions of Fig. 5 are shown in Fig. 4. The period of the cyclical varying current is represented by $2T$, therefore the interval between the mid-points of successive marking and spacing impulses is T and between the mid-points of successive marking or spacing impulses is $2T$.

In the actual transmission of a picture the picture current will vary from portion to portion between its maximum and minimum values and the type of impulses which will be impressed upon line 6 is represented by the current graph of Fig. 6.

From Fig. 6 it is evident that while the time interval between the mid-point of any marking or spacing interval to the mid-point of the succeeding marking or spacing interval respectively is constant and may be represented by $2T$, the length of time between the beginning of a marking or a spacing interval to the beginning of the succeeding marking or spacing interval respectively is continuously changing as the tone values of elemental areas of the picture change as shown by the distances f, g, h, i and k .

In the foregoing description of Fig. 1 it is assumed that an increase of current in the photoelectric cell 34 causes an increase of current in the output circuit of the amplifier 35. Thus for a dark spot on the picture a small amount of light passes to the photoelectric cell 34 and a small value of picture current flows in the winding 12 of relay 5. This corresponds, for example, to a value of current I_A in Fig. 5 and would result in a large ratio of marking to spacing on the reproduced record as represented by graph A in Fig. 5, and where the ratio of marking to spacing is large a dark condition is represented. Obviously then for a light spot the picture current will be large, for example, of the value represented by I_E in Fig. 5, the ratio of marking to spacing will be small, and the corresponding portion of the reproduced picture will be light. Obviously by reversing the connections to the relay contacts or reversing the action of amplifier 35 the ratio of marking to spacing can be made large for a light spot in the film and small for a dark spot.

Referring now to Fig. 2 a modified arrangement is employed. Relay 40 is quite similar to relay 5 of Fig. 1 having the three

energizing windings 41, 42, 43. Winding 43 is the steady biasing winding which is energized by current from battery 44 through resistance 45. Winding 42 is energized by picture current from the source 46 which may be identical with that shown in Fig. 1. The energizing current in winding 41 is also of saw-toothed wave form but this wave form is obtained in a different manner, i. e., by means of a variable resistance in series with the inductance of the relay winding.

The source of cyclically varying current in Fig. 2 consists of the winding 41 of relay 40 in series with resistance 47 upon which are impressed positive and negative potentials from batteries 48 and 49 respectively through the commutator 50 which is driven by a motor 51.

The action of the relay in impressing marking and spacing current on the line 6 is the same as in Fig. 1 which is indicated by the use of the same reference characters.

The commutator arrangement of Fig. 2 for producing potentials of opposite polarities in the source of cyclically varying current may be used in place of the vibrating relay of Fig. 1 and likewise the vibrating relay of Fig. 1 may be used in place of the commutator of Fig. 2.

In Fig. 3 an arrangement quite similar to that of Fig. 1 is shown except that winding 11 is energized by current of sine wave form obtained from generator 55. In this arrangement the length of the marking and spacing impulses are not directly proportional to the amplitude of the picture current and therefore distortion would be introduced into the reproduced picture. Under some circumstances this may not be objectionable and an improved result may actually be obtained in improving the contrast in the reproduced picture or other desired characteristics.

A suitable type of reproducer may be used which is operable by current impulses. The reproducers disclosed in Patent No. 1,613,970, Jan. 11, 1927, of D. C. Tanner, are mentioned by way of example. Synchronism must, of course, be maintained between the transmitting and reproducing drums. Arrangements for accomplishing this result are well known in the art.

In the arrangements selected for illustration of the invention the spacing and marking impulses are of opposite polarity. Obviously impulses of a single polarity may be used for marking and no current for spacing or vice versa. The type of impulses to be used is dependent upon the nature of the transmitting channel to be employed which may be a wire line, like line 6 of the drawings, either long or short, a wire carrier channel or a radio channel.

In order to assist in understanding the theory of the invention and to aid in the de-

sign of actual circuits, a mathematical explanation will now be given.

Referring to Fig. 3 the polar relay 5 is operated from a sine wave ($I_1 \sin \omega$), the contacts of this relay forming the telegraph signals shown in Figs. 4 to 6. The reproduced picture shade can be defined as

$$S_2 = \frac{t_1}{T} \quad (1)$$

which will vary from 0 to 1 as the bias varies from -100% to +100%. The relation between

$$\frac{t_1}{T}$$

and sending picture shade S_1 is

$$S_2 = \frac{t_1}{T} = \frac{1}{2} \left(1 - \frac{2}{\pi} \sin^{-1} \frac{I_2}{I_1} \right) = \frac{1}{2} \left(1 - \frac{2}{\pi} \sin^{-1} \frac{S_1}{I_1} \right) \quad (2)$$

It is seen that S_2 and S_1 are related by a sine function which is approximately linear over the central range, but will be distorted in the light and dark shades.

This difficulty of distortion will be overcome in the arrangement of Fig. 1 where the method used consists in charging a condenser 13 from a vibrating relay 18 delivering unbiased reversals and operating the signal forming relay 5 as a leak on the condenser, the current through the relay being proportional to the voltage across the condenser. The voltage across the condenser will build up exponentially according to the following equation

$$e_c = \frac{E}{R} (1 - e^{-\frac{1}{CR} t}) \quad (3)$$

This will be approximately linear for a short time and it is assumed that the charging potential reverses before departing materially from linearity. The approximate equation of the straight line representing the charging current for the first small interval of time is obtained by taking the first derivative and evaluating when $t=0$. That is

$$e_c = \frac{E}{CR^2} \cdot t \quad (4)$$

A saw-toothed wave will be obtained which has a slope

$$55. \quad \frac{E}{CR^2} \text{ from } 0 \text{ to } \pi/2, -\frac{E}{CR^2} \text{ from } \pi/2 \text{ to } \frac{3\pi}{2}, \text{ etc.}$$

Let I_o represent the current when the reversal takes place, i. e., the peak value of the saw-toothed wave. Then the reproduced shade and the original shade are related as follows

$$S_2 = \frac{t_1}{T} = \frac{1}{2} \left(1 - \frac{S_1}{I_o} \right) \quad (5)$$

As $\frac{S_1}{I_o}$ varies from +1 to -1 the reproduced

shade will vary linearly from 0 to 1. Equation (5) neglects the effect of the shunt on the condenser and the inductance of the relay and assumes infinite sensitivity; consequently it only approximately represents the actual condition.

The voltage across the condenser will rise approximately linearly with the time until

$$t = \frac{1}{2} CR \quad (6)$$

which forms a basis for the design of the circuit constants. Assume that the reversal frequency is 10, that is a 10 dot per second signal is to be biased from -100 per cent. to +100 per cent. Then

$$t = \frac{1}{20} = \frac{1}{2} CR \quad (7)$$

$$\text{if } C = 10 \text{ MF}$$

$$R = \frac{2}{20} \times \frac{10^6}{10} = 10,000 \text{ ohms.} \quad (8)$$

from (4)

$$e_c = \frac{E}{CR^2} \cdot t = \frac{100}{10 \times 10^{-6} \times 10^8} \cdot \frac{1}{20} = 50 \text{ (max)} \quad (9)$$

That is the condenser voltage rises to 1/2 of its final steady state value (with no re-

versal) in $\frac{t}{2}$ seconds. The peak value of the saw-toothed wave will be 1/2 of this or 25 volts.

In the circuit of Fig. 2, which accomplishes the same thing but which differs in that the current through an inductance instead of voltage across a condenser is being considered. The current wave is given by the following

$$i_L = \frac{E}{R} (1 - e^{-\frac{R}{L} t}) \quad (10)$$

Proceeding as before the equation of the approximate straight line is

$$i_L = \frac{E}{L} \cdot t \quad (11)$$

The relation between reproduced and original shade is the same as Equation (5), namely

$$S_2 = \frac{t_1}{T} = \frac{1}{2} \left(1 - \frac{S_1}{I_o} \right) \quad (5)$$

A comparison of Equations (10) and (3) shows the wave shape to be identical when

$$L = CR^2 \quad (12)$$

That is when $R = 10^4$ and

$$C = 10 \times 10^{-6}$$

$$L = 10 \times 10^{-6} \times 10^8 = 1000 \text{ henries} \quad (13)$$

which is probably impractical.

However, it is not necessary to have R as

high as 10,000 ohms. The design equation for this circuit is

$$t = \frac{1}{2} \frac{L}{R} \quad (14)$$

5 for a 10 cycle signal, we get

$$t = \frac{1}{20} = \frac{1}{2} \frac{L}{R}$$

$$R = 10L \quad (15)$$

10 R could then be made 1000 ohms and L=100 henries which is entirely practical.

If in either Fig. 1 or Fig. 2 there is a 15 tendency to spark, this could be prevented by a "spark killer" circuit bridged across the contacts. In Fig. 1 the spark killer would be a resistance and inductance in series and in Fig. 2 it would be a resistance and condenser in series. The theoretical 20 equation governing their design would be the same in each case, namely

$$L = CR^2$$

25 and if R_1 was made = R_2 , the circuit would act like a pure resistance. Practical considerations might probably prevent making $R_1 = R_2$.

What is claimed is:

30 1. In a signaling system, a movable circuit controlling element, means for applying a linearly varying periodic force to said element to actuate it, and means for applying a biasing force to said element which varies in accordance with signals.

35 2. In a signaling system, a relay, means for biasing the armature of said relay, means for impressing upon said relay a linearly varying periodic current of constant amplitude, and means for varying the amount of bias of said armature in accordance with signals.

40 3. In a picture transmission system, a relay, a source of direct potential, a transmission circuit, the armature of said relay 45 controlling the association of said source with said transmission circuit, a source of linearly varying periodic current of constant amplitude for actuating said relay, and means for varying the bias of the armature of said relay 50 in accordance with the tone values of the elemental areas of the picture or object to be transmitted whereby the length of time during which said source of direct potential is associated with said transmitting circuit corresponds to said tone values.

55 4. In a signaling system, a source of periodically varying current, a source of current varying in accordance with signals, a transmitting circuit, a source of signaling voltage, 60 switching means for associating said source of signaling voltage with said transmitting circuit, said switching means being acted upon by said source of periodically varying current so as to tend to actuate it in one direction and by said second source of varying

current so as to tend to actuate it in the opposite direction.

5. In a picture transmission system, a source of periodically varying current, a source of varying current modulated in accordance with the tone values of the elemental areas of the picture to be transmitted, a transmitting circuit, a source of signaling voltage, and switching means for associating said source of signaling voltage with said transmitting circuit, said switching means being actuated by said periodically varying current to tend to move said switching means in one direction and by said second source of varying current to tend to move said switching means in the opposite direction. 70 75 80

6. In a picture transmission system, a source of alternating current, a source of pulsating current of amplitude corresponding to the tone values of elemental areas of a picture to be transmitted, a source of steady biasing current, means for producing magnetic effects by currents from said sources, the effects produced by the two last mentioned sources being in opposition, and switching means actuated by said magnetic effects to produce code impulses. 85 90

7. In a picture transmission system, a source of alternating current waves, having a form which rises and falls substantially linearly with time, a relay energized by current from said source, an armature for said relay which vibrates under the influence of said alternating current energization, means to produce a steady bias in said relay, a second source of pulsating current of amplitude corresponding to the tone values of elemental areas of a picture to be transmitted, and means to oppose the steady bias by current from said second source for controlling the duration of the intervals between movements of the armature. 95 100 105

8. In a picture transmission system, a current operated switching device, means for impressing current upon said device for causing a switching operation during successive equal time intervals, means for determining the time of initiation of a switching operation in accordance with the tone values of elemental areas of a picture to be transmitted, and means for producing impulses of current controlled by said switching device. 110 115

9. In a picture transmission system, a series circuit comprising a resistance, a condenser and a source of current, a vibrating relay having contacts in said series circuit adapted to change the polarity of said source at uniform intervals, a multi-winding polarized relay, an energizing circuit for one winding of said relay connected in shunt of said condenser, a resistance connected in series in said energizing circuit, a source of signaling current connected to a second winding, a contact closing armature controlled jointly by said two windings, and a signaling circuit, 120 125 130

the current in which is controlled by said armature.

10. In a picture transmission system a series circuit comprising a resistance, a condenser and a source of current, a vibrating relay having contacts in said series circuit adapted to change the polarity of said source at uniform intervals, a multi-winding polarized relay, an energizing circuit for one winding of said relay connected in shunt to said condenser, a resistance connected in series in said energizing circuit, a source of picture current connected to a second winding, said source comprising a photoelectric cell, an amplifier and means to illuminate the photoelectric cell in accordance with the tone values of a picture, a contact closing armature controlled jointly by said two windings and a transmission circuit the current in which is controlled by said armature.

11. In a picture transmission system, means for producing electrical current impulses of the same polarity during successive equal time intervals, and means for determining the time of initiation of said impulses in accordance with the tone values of elemental areas of a picture to be transmitted.

12. In a picture transmission system, means for producing electrical current impulses of the same polarity during successive equal time intervals, and means for determining both the time of initiation and of the termination of said impulses in accordance with the tone values of elemental areas of a picture to be transmitted.

13. In a signaling system, a series circuit comprising a resistance, a condenser, and a source of current, means to change the polarity of said source at uniform intervals, a translating device having an energizing circuit connected in shunt to said condenser only, whereby said translating device is energized by alternating energy having a wave form which rises and falls substantially linearly with time and means associated with said translating device for propagating signals.

14. In a picture transmission system, a source of alternating current waves of substantially sinusoidal wave form, a relay energized by current from said source, an armature for said relay which vibrates under the influence of said alternating current energization, means to produce a steady bias in said relay, a second source of pulsating current of an amplitude corresponding to the tone values of elemental areas of a picture to be transmitted, and means to oppose the steady bias by current from said second source for controlling the duration of the intervals between movements of the armature.

15. In a signaling system, a series circuit comprising a resistance, an inductance, and a source of current, means to change the polarity of said source at uniform intervals, the

value of the resistance and inductance being so proportioned that the time constant of the series circuit is appreciably greater than the interval of time between changes of polarity of said source, to produce an alternating current in said inductance having a wave form which rises and falls substantially linearly with time, a movable circuit controlling element, means for applying to said element to actuate it, a linearly varying periodic force produced by said alternating current, and means for applying a biasing force to said element which varies in accordance with signals.

16. In a picture transmission system a series circuit comprising a resistance, an inductance, and a source of current, means to change the polarity of said source at uniform intervals, the value of the resistance and inductance being so proportioned that the time constant of the series circuit is appreciably greater than the interval of time between changes of polarity of said source, to produce an alternating current in said inductance having a wave form which rises and falls substantially linearly with time, a relay energized by said alternating current, an armature for said relay which vibrates under the influence of said alternating current waves, means to produce a steady bias in said relay, a second source of pulsating current of amplitude corresponding to the tone values of elemental areas of a picture to be transmitted, and means to oppose the steady bias by current from said source for controlling the duration of the intervals between movements of the armature.

In testimony whereof, I have signed my name to this specification this 9th day of February, 1927.

DISCLAIMER

1,788,476.—*Edward F. Watson*, Larchmont, N. Y. ELECTRICAL PICTURE TRANSMISSION. Patent dated January 13, 1931. Disclaimer filed August 16, 1935, by the assignee, *American Telephone and Telegraph Company*.

Hereby enters this disclaimer to the subject-matter of the said claims of said Letters Patent which are in the following words, to wit:

“4. In a signaling system, a source of periodically varying current, a source of current varying in accordance with signals, a transmitting circuit, a source of signaling voltage, switching means for associating said source of signaling voltage with said transmitting circuit, said switching means being acted upon by said source of periodically varying current so as to tend to actuate it in one direction and by said second source of varying current so as to tend to actuate it in the opposite direction.

“5. In a picture transmission system, a source of periodically varying current, a source of varying current modulated in accordance with the tone values of the elemental areas of the picture to be transmitted, a transmitting circuit, a source of signaling voltage, and switching means for associating said source of signaling voltage with said transmitting circuit, said switching means being actuated by said periodically varying current to tend to move said switching means in one direction and by said second source of varying current to tend to move said switching means in the opposite direction.”

“8. In a picture transmission system, a current operated switching device, means for impressing current upon said device for causing a switching operation during successive equal time intervals, means for determining the time of initiation of a switching operation in accordance with the tone values of elemental areas of a picture to be transmitted, and means for producing impulses of current controlled by said switching device.”

“11. In a picture transmission system, means for producing electrical current impulses of the same polarity during successive equal time intervals, and means for determining the time of initiation of said impulses in accordance with the tone values of elemental areas of a picture to be transmitted.

“12. In a picture transmission system, means for producing electrical current impulses of the same polarity during successive equal time intervals, and means for determining both the time of initiation and of the termination of said impulses in accordance with the tone values of elemental areas of a picture to be transmitted.”
